United States Patent Office.

JOHN GORHAM, OF PROVIDENCE, RHODE ISLAND, ASSIGNOR TO GORHAM MANUFACTURING COMPANY:

Design No. 2,854, dated December 31, 1867.

DESIGN FOR A TRADE-MARK.

The Schedule referred to in these Letters Patent and making part of the same.

TO ALL WHOM IT MAY CONCERN:

Be it known that I, JOHN GORHAM, of the city and county of Providence, and State of Rhode Island, have originated and designed a new Design for a Trade-Mark, of which the following is a full, clear, and exact description, reference being had to the accompanying drawings; making part of this specification.

My said design for a trade-mark consists of an anchor on a shield, such as is shown in the said drawings, A being an anchor and S a shield. And my design further consists of the legend or inscription, Gorham Mfg Co., as shown in the said drawings.

This mark I purpose using, arranged one above the other, or otherwise, in connection, to designate and distinguish the genuine manufacture or article of "electro-plated ware," (so called,) of the corporation or company authorized and doing business under the name and style of the "Gorham Manufacturing Company," the said marks being stamped or otherwise fixed on the said manufacture in any well-known and effective manner.

Claim.

What I claim as my invention, and desire to secure by Letters Patent, is—
The design for a trade-mark herein set forth.

JOHN GORHAM.

Witnesses:

ISAAC A. BROWNELL,
A. T. GORHAM.
